CORDLESS GRASS SHEAR

Peter Cosmos, Sr., Ashtabula, Ohio, assignor to True
Temper Corporation, Cleveland, Ohio

Filed Sept. 21, 1972, Ser. No. 290,959

Term of patent 14 years

Int. Cl. D8—03

U.S. Cl. D8—8

Fig. 1

Fig. 2

Fig. 3

Fig. 4

Fig. 5

Fig. 6

FIG. 1 is a side elevation of the cordless grass shear showing my new design;

FIG. 2 is a top plan view thereof;

FIG. 3 is a front elevation thereof;

FIG. 4 is an opposite side elevation thereof;

FIG. 5 is a bottom plan view thereof; and

FIG. 6 is a rear elevation thereof.

I claim:

The ornamental design for a cordless grass shear, as shown.
